UNITED STATES PATENT OFFICE.

EPHRAIM D. KLOTS, OF NEW YORK, N. Y.

APPARATUS FOR GENERATING TERPENE OZONID VAPOR.

1,386,410.

Specification of Letters Patent. Patented Aug. 2, 1921.

Application filed June 6, 1916. Serial No. 101,955.

To all whom it may concern:

Be it known that I, EPHRAIM D. KLOTS, a citizen of the United States, residing in the city, county, and State of New York, have 5 invented certain new and useful Improvements in Apparatus for Generating Terpene Ozonid Vapor; and I do hereby declare the following to be a full, clear, and exact description of the invention, such as will enable others skilled in the art to which it appertains to make and use the same.

This invention relates to apparatus for generating a medicinal vapor from a substance of the terpene group such as pinene. 15 The invention is directed to the provision of an improved form of apparatus of this character which is simple in construction, which may be manufactured at low cost, which is of light weight and small bulk, 20 which may be readily cleaned and kept in a sanitary condition, and which is well adapted for household use involving operation of the apparatus by unskilled persons and requiring that the danger of injury to the operator 25 be completely eliminated.

In apparatus of this character as heretofore constructed, it has been common to provide an ozonizer for generating ozone, means for vaporizing the terpene and a mixing chamber in which the vapor of terpene and the ozone are mixed. Such an apparatus is elaborate, cumbersome, expensive and both difficult to operate and difficult to keep clean, and its use has been greatly restricted 30 for these reasons. The present invention involves the provision of an apparatus of an improved construction such that all of the objectionable features which have characterized the apparatus heretofore employed, including those pointed out above, are eliminated.

One of the features of primary importance in an apparatus constructed in accordance with the present invention involves the combining of the elements for generating ozone and for generating terpene ozonid vapor in a single chamber, eliminating the use of a separate mixing chamber and avoiding the danger of escape of free ozone. The apparatus for generating ozone is mounted within a suitable casing and the receptacle for the terpene is placed directly in this casing so that as the ozone issues from the ozonizer it comes into direct contact with the liquid 55 terpene in the receptacle. When this occurs, a vapor of ozonized terpene is gener-

ated which rises from the receptacle in a thick white cloud and may be directed to the point of use in any suitable or convenient manner. The placing of the ozonizer close 60 to the receptacle for the terpene so that the ozone generated comes at once into direct contact with the liquid terpene is a feature of great importance. The construction is greatly simplified, the size, cost and number 65 of parts in the structure are greatly reduced and the danger of the escape of free ozone is practically eliminated. Furthermore, the air which is forced through the ozonizer with a moderate velocity sufficient to maintain 70 the necessary supply of air serves to prevent undue heating of the ozonizing apparatus and at the same time the comparatively slight elevation of the temperature in and about the ozonizer serves to warm 75 the terpene to the extent desirable for accomplishing the vaporization thereof freely.

The invention also involves the compact arrangement of the necessary parts of the apparatus so as to form a complete unit of 80 relatively small dimensions which may be readily carried from place to place, if desired, by hand. To this end a rectangular casing is provided having a vertical partition dividing it into two sections, one containing a vapor generating apparatus and the other containing the electrical devices. The electrical devices include a transformer for raising the voltage to that required in the ozonizer and a rotary fan for maintaining 85 a current of air through the ozonizer. A small electric motor is preferably employed for driving the fan and when the apparatus is to be connected in a direct current circuit, this motor may be combined with a 90 suitable rotary converter for converting the direct current into alternating current.

Preferably a small rotary converting machine of the type known as a dynamotor is provided for supplying alternating current 100 to the transformer and the fan is secured upon the end of its shaft. The ozonizer is mounted within the other compartment of the casing, preferably in a vertical position, it being connected at its upper end to the 105 conduit leading from the fan and having the receptacle for the liquid terpene positioned under its lower end. These parts, namely the ozonizer and the receptacle for the terpene, are preferably arranged within 110 an inner casing within which the generation of the ozone and the vaporizing and ozoniz-

ing of the terpene take place, as in this way the escape of free ozone is prevented and the heat developed as an incident to the generation of ozone may be readily regulated so as to guard against an excessive rise of temperature and at the same time utilize such heat as is developed to warm the terpene to the point at which it vaporizes readily.

10 Another feature of the invention involves the arrangement of the parts in such a way as to permit them to be readily detached for cleaning and then reassembled. To this end a receptacle is provided for the terpene 15 which may be readily moved into position and withdrawn therefrom. Also, the inner casing within which the ozonizer and the receptacle for terpene are mounted is so constructed that it may be readily opened 20 and that when opened it permits free removal of the parts contained therein including the entire ozonizer.

The invention includes numerous other features of improvement including the construction and mounting of the parts of the ozonizer, the provision of detachable connections in the air conduit and the electrical circuits to facilitate removal of the parts, a throttling device for controlling the air current and the arrangement of the parts of the ozonizer so that they may be readily disassembled for cleaning and then reassembled.

These and other features of the invention will be better understood by reference to the 35 following description taken in connection with the accompanying drawings which illustrate the preferred embodiment of the invention.

In these drawings, Figure 1 is a vertical 40 section of the apparatus through the ozonizer and the receptacle for the terpene; Fig. 2 is a vertical section through the casing showing the electrical devices; Fig. 3 is a horizontal section through the upper portion of the casing above the ozonizer and dynamotor; Fig. 4 is a detail view in transverse section showing the ozonizer and the compartment in which it is mounted; Fig. 5 is a detail view in vertical section showing the throttling 45 device for the air conduit; Fig. 6 is a detail view in vertical section showing a modified construction which may be employed at the lower end of the ozonizer; and Fig. 7 is a view similar to Fig. 1 and illustrating a modified construction which I may employ.

Referring to these drawings, 7 indicates a rectangular casing provided with a vertical partition 8 dividing the casing into front and rear compartments. Opposite sides of the 60 casing are provided with hinged doors 23 and 24 which may be opened to give access to the compartments. In the rear compartment is a shelf 9 upon which is mounted a dynamo-electric machine 10. When the apparatus is to be used upon an alternating cur-

rent circuit, this machine 10 is an alternating current motor. When the apparatus is to be used upon a direct current circuit, this machine 10 is a rotary converter, as is shown in the drawings. The shaft of the machine 10 is extended beyond one of its bearings and has the rotary element 11 of a fan mounted thereon. The blades of this fan rotate within a casing 12 provided with a central inlet opening 13, the walls of which extend through an opening in the side of the casing 7. The outlet 14 from the casing 12 of the fan is connected to a conduit 15 which carries air from the fan to the ozonizer.

In the rear compartment of the casing 7 and below the shelf 9 is a transformer having a primary coil 16 and secondary coils 17. The primary coil 16 may be provided with a plurality of taps 18 as shown in Fig. 2 which may be utilized in selected pairs to obtain the voltage desired for the current flowing in the circuit of the secondary coils 17. The electrical connections of the parts so far described are shown in Fig. 2. The incoming wires 19 lead to the converter 10, a safety device 20 being inserted in one of the wires. From the converter 10, wires 21 lead to a selected pair of the taps 18 of the primary coil 16 of the transformer, a safety device 20 being inserted in one of these wires 21 if desired. Wires 22 lead from the secondary coils of the transformer through openings in the vertical partition 8 to the ozonizer.

Within the compartment at the front of the casing is an inner casing or compartment 100 within which is the ozonizer and the receptacle for the liquid terpene and wherein the terpene ozonid vapor is generated. This inner casing has a rear wall 25 and a side wall 26 rigidly mounted upon the central partition 8 of the main casing and it has a side wall 27 and a front wall 28 which are connected by a hinge to the outer edge of the side wall 26. When these walls are in the positions shown in Fig. 4, they form an inner compartment of rectangular cross-section. The coacting portions of the hinged and fixed walls are provided with vertical grooves for the reception of gaskets 29 so that when the inner compartment is closed, it is substantially air-tight. At the inner edge of the movable wall 27 are suitable latches 30 whereby the parts of the inner casing may be maintained in the closed position. This inner compartment is closed at the lower end thereof by a bottom wall 31, one-half of which is of triangular form and secured to the walls 25 and 26 and the other half of which is of triangular form and secured to the walls 27 and 28. The upper end of the inner compartment is similarly closed by a top wall 32, one-half of which is of triangular shape and secured to the walls 25 and 26 and the other half of which is of triangular form and secured to the walls 27 130

and 28. These parts of the top wall 32 have semi-circular portions cut therefrom so that when the compartment is closed a circular opening is provided in this top wall 32.

5 The ozonizer is supported upon the top wall 32 of the inner compartment and extends downward vertically to a point near the bottom of the compartment. The parts of the ozonizer are mounted upon a metallic 10 tube 33 preferably made of aluminum. Its size approximates the size of the circular opening in the top wall 32 of the compartment and at its upper end is an integral flange 34. An annular gasket 35 formed of 15 insulating material and consisting of two separable semi-circular pieces is mounted upon the two portions of the top wall 32 and the flange 34 of the tube 33 is adapted to rest upon this gasket 35. On the upper surface 20 of the flange 34 is an annular gasket 36 of insulating material. The upper end of the tube 33 is adapted to be closed by a disk 37, preferably made of glass, having a central opening therethrough. This disk 37 is held 25 in position by means of a ring 38 having an internal flange 39. This ring is clamped in position by means of screws 40 whose threaded ends enter openings in the flange 34 and it serves to hold the disk 37 of glass 30 in position.

The metallic tube 33 forms one electrode of a silent discharge, high tension electric ozonizer. The other electrode of the couple consists of a metallic film or coating 41 upon 35 the interior surface of a glass cylinder or bottle 42. This bottle is mounted within the tube 33 with its cylindrical wall separated from the wall of the tube 33 by a narrow space approximating one-sixteenth of an 40 inch. Preferably the cylinder 42 is held in position concentric with the tube 33 by means of spacers 43 of non-oxidizable material at the upper and lower ends of the bottle, these elements 43 being spaced apart circumferentially of the bottle so as to provide 45 passages for air between them.

The bottle 42 is closed at its lower end, as shown, and at its upper end it is provided with a central opening of substantial size.

50 A tube 44 of glass extends downwardly through the central opening in the disk 37 and through the opening in the upper end of the bottle 42 to a point close to the lower closed end of the bottle 42. It may be sustained in position by a clamp 45 gripping the tube 44 and bearing upon a gasket 46 which bears upon the glass disk 37.

At its upper end the tube 44 is bent laterally and the end of the horizontal portion 60 enters one end of a coupling 47 (Figs. 3 and 5). The other end of this coupling receives the end of the conduit 15 leading from the fan. Within the coupling is a throttle valve 48 mounted upon a shaft 49 which is rotatable in a fitting 50 secured to the under

side of the top of the main casing 7. On the upper end of the shaft 49 is a finger piece 51 to which access is had through an opening in the top wall of the casing 7, as shown in Fig. 5.

70 Electrical connection is made to the metallic film or coating 41 on the interior of the bottle 42 by means of an insulated wire 52 which enters the tube 44 through a bushed opening in the lumen of the tube 44. The 75 wire 52 extends downwardly to the end of the tube 44 concentric therewith and its lower end is electrically connected to the metallic coating 41, preferably by having a plurality of chain links 53 connected to the 80 lower end of the wire and resting by gravity upon the lower closed end of the bottle 42. The wire 52 is connected to one of the wires 22 shown in Fig. 2. The other of the two wires 22 is connected to a binding post 54 85 mounted upon the stationary portion of the top 32 of the inner compartment. This binding post 54 has a contact spring 55 secured thereto and projecting toward the tube 44 so that when the parts are in the positions 90 shown in Figs. 1 and 3, this spring arm 55 bears upon the upper surface of the ring 38 and thus makes electrical connection with the ring and the tube 33 to which it is secured.

95 Within the inner compartment and below the lower end of the tube 33 is a space for the reception of a receptacle 59 for the liquid terpene. This receptacle is preferably of rectangular form and fits snugly 100 within the compartment but it may be readily withdrawn from the compartment when the latter has been opened. The compartment is opened by releasing the latches 30 and turning the walls 27 and 28 about their 105 hinged connection to the wall 26, carrying one-half of the top wall 32 away from the tube 33. The entire ozonizer may then be moved forward horizontally out of the compartment and in moving the ozonizer thus 110 the ring 38 slides out from under the spring arm 55 and the horizontal end of the tube 44 slides out of the coupling 47. In the wire 52 is a detachable connection which may be broken to permit of the entire removal of the ozonizer.

115 The front wall 28 of the inner compartment preferably consists of a rectangular frame with a pane of glass set therein and the door 24 of the main casing may also have 120 a sheet of glass therein so that it is possible to see the parts within the inner compartment at all times. The vapor generated within the compartment rises therein and passes out through a tube 56. The lower end 125 of this tube fits tightly within an opening in the stationary portion of the top 32 of the inner compartment and the tube extends upwardly through an opening in the top of the casing 7.

Fig. 6 shows a slight modification of the construction shown in Fig. 1, wherein the lower end of the tube 33 is threaded to receive a cap 57 to which a tube 58 is connected. 5 This construction may be employed when it is desired to use a closed receptacle for the liquid terpene and to convey the ozone from the ozonizer to this receptacle, the receptacle being provided with a separate outlet tube 10 for the vapor generated therein.

With the apparatus thus constructed, the operation is as follows: When the electric circuit to the converter 10 is closed, the direct current flows to the converter and alternating current flows from it to the transformer, the rotor of the converter being set in rotation and driving the rotary element of the fan. High tension current flows from the secondary coils of the transformer 15 through one of the wires 22 to the wire 52 and then to the metallic film 41 upon the interior of the cylinder 42. From the other electrode 33 of the ozonizer the current returns to the transformer through the spring 20 arm 55 and the wire 22 connected to the binding post 54. The flow of current in this circuit is accompanied by a high tension discharge across the narrow gap between the electrodes 41 and 33 and this discharge 25 generates ozone. The air drawn into the casing by the fan 11 is forced through the pipe 15 and tube 44 and issues from the lower end of the tube into the cylinder 42. It passes upwardly through this cylinder and out at its 30 upper end into the interior of the cylinder 42 and then passes downwardly through the narrow annular space between the parts 33 and 42. While the air is flowing through this narrow annular space, the ozone is generated by the high tension electric discharge. 35 The ozone issuing from the lower end of the tube 33 comes into direct contact with the liquid terpene in the receptacle 59 and its contact therewith causes the generation of 40 terpene ozonid vapor. This vapor rises from the receptacle 59 and moves with the current upwardly within the inner compartment and passes out through the tube 56 in the form of a dense, light cloud. The current of air 45 passing through the ozonizer by this tortuous route carries off heat to such an extent as to prevent the parts of the ozonizer from being raised to an objectionably high temperature by the heat developed by the electric discharge. 50 The temperature within the ozonizer is raised somewhat but such a rise in the temperature not only is not objectionable but on the contrary is advantageous in that it 55 warms the liquid terpene enough to facilitate 60 the vaporization thereof.

Another of the advantageous characteristics of the construction herein illustrated and described is that the apparatus is largely self-regulating. In apparatus of the types 65 heretofore employed wherein terpene vapor

and ozone have been separately generated and subsequently intermingled, difficulty has been experienced in maintaining the proper proportion of the two ingredients. In the apparatus above described, the ozone issues from the outlet end of the ozonizer and comes directly into contact with the liquid terpene in the adjacent receptacle. The terpene ozonid vapor is generated immediately by the contact of the ozone with the liquid in the receptacle and the amount of the vapor to be generated is therefore directly proportional to the amount of ozone generated in the ozonizer and carried into contact with the liquid terpene. Therefore 70 the apparatus is in this respect self-regulating, the amount of the terpene ozonid vapor being directly proportional at all times to the amount of ozone generated. The control of the apparatus is effected by means of the 75 hand-operated throttle valve in the air conduit whereby the freedom of flow of air from the fan to the ozonizer may be increased or diminished as desired. As this freedom of flow is changed, the volume of air passing 80 through the ozonizer is changed, correspondingly effecting the amount of ozone generated and with it the rate of ozonation of the terpene.

Another of the important characteristics 85 of the machine above described is the readiness with which certain of the parts may be removed, particularly the parts which will require cleaning from time to time when the apparatus is in use. This is particularly true 90 of the receptacle for the terpene which should be cleaned from time to time in order that the vapor may be of the highest medicinal value. In order to remove this receptacle it is only necessary to open the 95 hinged doors of the main casing and the inner compartment. Furthermore, the ozonizer should be cleaned from time to time in order that the best results may be obtained 100 and the apparatus is so constructed as to facilitate removal, disassembly, cleaning and reassembly of the ozonizer. When the doors of the outer casing and the inner compartment are opened, the entire ozonizer is 105 free to be drawn forward horizontally, 110 breaking the air and electrical connections thereto. Then the inner tube and the glass bottle may be removed from the outer metallic cylinder.

One of the most important features of the 115 apparatus is the provision of a chamber within which are both the ozone generating apparatus and the terpene and from which the terpene ozonid vapor issues. By reason of the provision of such a construction, the 120 danger of the liberation of free ozone is practically eliminated. The compartment bounded by the walls 25, 26, 27 and 28 contains all the elements of the ozonizer and as 125 the ozone issues from the ozonizer it comes 130

at once into contact with the ozone in the tray 59 also located within the compartment. The chemical reaction between terpene and ozone takes place practically instantaneously. Therefore, the ozone issuing from the ozonizer tube directly upon the surface of the liquid terpene is immediately consumed in the formation of the terpene oxonid which precludes any possible escape of free ozone. This is of special importance in an apparatus to be used for medicinal purposes, as free ozone is not only objectionable but deleterious. Notwithstanding the mounting of the ozonizer and the terpene receptacle within the same chamber and in close juxtaposition, these parts are so mounted that they are readily accessible and can be removed, cleaned and restored as desired.

Fig. 7 illustrates a modified construction which may be employed in lieu of that shown in the other figures. The characteristic feature of this modified construction is the same as that of the construction shown in Fig. 1, namely that the ozonizer and the material to be ozonized are both located within the same inclosure so that ozone issuing from the ozonizer comes in direct contact with the material from which the oxonid vapor is to be formed, and that this inclosure may be readily removed so as to permit of the necessary cleaning. In Fig. 7, the inclosure consists of a glass jar closed at its lower end and the bottom portion of this jar constitutes the receptacle for the liquid terpene and the ozonizer is adapted to be mounted within the upper portion of the jar. This construction is more simple and more economical than that shown in Fig. 1 and the parts of the receptacle can be more readily kept clean.

Referring to the Fig. 7 construction more in detail, the jar constituting the inclosure for the ozonizer and the terpene is shown at 70. It is preferably made of glass and is closed at its lower end. The upper end of the inclosure or jar is flanged, as indicated at 71. This jar is adapted to be seated within a circular wall 72 located upon the bottom of the casing and it is held from lateral movement by means of spring arms 73 which partially embrace the jar. The ozonizer shown in Fig. 7 is similar in construction to that illustrated in the preceding figures and it is sustained in position by a cover 74 for the jar 70. This cover is made of an insulating material, it is circular in form and it is provided with an opening through which the ozonizer extends, the flange at the top of the ozonizer resting upon the upper surface of the cover 74. A gasket 75 is preferably placed between the cover 74 and flange 71. A vapor outlet tube is shown at 76 projecting through an opening in the casing of the apparatus and also

through an opening provided in the cover 74. Preferably, the position of the ozonizer is slightly eccentric to the jar 70 to increase the space on one side for the tube 76. Because of this, pins 77 are preferably provided in the cover 74 in position to enter openings provided for their reception in the flange 71 of the jar 70. By reason of the provision of these pins and openings, the jar and cover must necessarily be brought to the appropriate positions when assembling the parts.

With this Fig. 7 construction, the bottom of the jar 70 is employed as the receptacle for the liquid terpene and the ozone issuing from the lower end of the outer ozonizer tube 33 comes into direct contact with the liquid terpene below the ozonizer. The vapor formed as a result of this contact of ozone and terpene rises within the jar and passes out through the outlet tube 76.

It will be seen that, as in the Fig. 1 construction, the ozonizer and the liquid terpene are inclosed within a single chamber, so that escape of free ozone is effectually guarded against. In order to clean the parts or to renew the supply of the liquid terpene, the outlet tube 76 is first withdrawn from the opening in the cover 74 and then the jar 70 is raised slightly so as to free it from the positioning flange 72. Then the entire jar 70 and the parts mounted thereon are moved forwardly and the air tube 44 is withdrawn from the coupling 47. Thereafter, the entire ozonizer may be drawn up out of the opening in the cover 74 and the latter removed from the jar 71 so that all of the parts may be readily cleaned and a new supply of the terpene placed in the bottom of the jar 70.

While I have illustrated and described herein the construction which I believe to be best adapted for use in practising my invention, I wish it understood that the invention is not limited to features of construction, as these may be varied between wide limits. Many of the parts of the ozonizer may be made of moldable insulating material such as bakelite; this is particularly true of the cover for the ozonizer chamber. Also, the outer electrode 33 of the ozonizer may consist of a tube of bakelite with an aluminum tube inserted therein. By employing such a construction, an economy in manufacture is attained, as then the aluminum tube may be a piece cut from a length of tubing and may not require a special machine. Furthermore, I have described the inner electrode as consisting of a glass cylinder having a metal coating applied to its inner surface in any suitable manner, as by flowing it thereon or electro-depositing it thereon; instead, however, the metal coating of the inner electrode may be a cylindrical sheet removably applied to the interior surface of the glass

cylinder of the inner electrode. With this latter construction there is less danger of breaking down the insulation between the two electrodes and the cost of maintaining the apparatus at this high efficiency is therefore substantially reduced.

I claim:

1. A vapor-generating apparatus comprising the combination of a casing, a motor and a blower driven thereby mounted within the casing, an inner compartment located within the casing, an ozonizer mounted within the inner compartment and so constructed that the air passage therethrough doubles back and forth upon itself, a receptacle for the liquid to be ozonized located within the inner compartment and close to the outlet of the ozonizer, a door for the inner compartment permitting removal of the receptacle, a conduit carrying air from the blower to the ozonizer, and an outlet for vapor from said inner compartment.
2. A vapor-generating apparatus comprising the combination of a receptacle closed at its lower end, the lower end of the receptacle being adapted to receive the material to be ozonized, an ozonizer mounted within the receptacle, a closure for the upper end of

the receptacle, an outlet from the receptacle, means for forcing air into and through the ozonizer to cause ozonized air issuing from the ozonizer to be directed upon the surface of the material to be ozonized at the lower end of the receptacle, and means for supplying high tension electric currents to the electrodes of the ozonizer.

3. A vapor-generating apparatus comprising the combination of an ozonizer consisting of concentric tubular members open at opposite ends to provide an air passage through the ozonizer which doubles back and forth upon itself, two of said tubular members having metallic surfaces which constitute electrodes, means for supplying high tension electric current to the electrodes, a blower, a connection with the blower to the upper end of the ozonizer, an outlet from the ozonizer at the lower end thereof, means for supporting a liquid to be ozonized directly under the outlet from the ozonizer so that ozonized air issuing from the ozonizer is directed upon the surface of said liquid, an inclosure for the ozonizer and an outlet for vapor from said inclosure.

In testimony whereof I affix my signature.

EPHRAIM D. KLOTS.
